LIGHTNING ARRESTOR FOR TELEVISION
TRANSMISSION LINES, ETC.Ernest O. Johnson, Haddonfield, N. J., assignor to
Radio Corporation of America, a corporation of
Delaware

Application May 1, 1947, Serial No. 745,205

5 Claims. (Cl. 201—63)

1

This invention relates to improvements in electrical connectors for tapping a plural wire signal-transmission line and will be described as embodied in a lightning arrestor unit for a television receiver installation.

As is well known, "dipole" and other antennas employed in television receiver installations may acquire very high static charges from the ambient atmosphere, even in the absence of lightning. Hence, safety requirements dictate the provision of a tap at a convenient point in the transmission line between the antenna and the receiver, for grounding such charges. The usual lightning arrestor tap comprises an elongated porcelain cylinder containing a resistor and a row of binding posts to which the wires of the transmission line are separately connected. The principal objection to such taps resides not alone in the mechanical difficulties incident to mounting the porcelain cylinder and in cutting, spreading and connecting the wires to the binding posts, but also in the fact that these several operations give rise to a "bump" (i. e., an abrupt change in impedance) or other electrical discontinuity in the line.

Accordingly, the principal object of the present invention is to provide a lightning arrestor which, when connected to a television or similar (high frequency) transmission line, introduces substantially no electrical discontinuity in the line and one which, in its attachment, dispenses with the cable-slitting, splicing and soldering operations required in the installation of comparable prior art units.

Another and important object of the invention is to provide a lightning arrestor which shall meet all of the standards of safety required of such devices and one nevertheless characterized by its low price and its low cost of installation.

Another and related object of the present invention is to provide a lightning arrestor unit which, by reason of the simplicity and economy of its parts, lends itself readily to mass production methods.

In the drawing:

Fig. 1 is an exploded view of a lightning arrestor unit constructed in accordance with the principle of the invention;

Fig. 2 is a top plan view and Fig. 3 is a sectional view, taken on the line III—III of Fig. 2 showing the device of Fig. 1 assembled and installed upon a convenient support for use in grounding a conventional two wire transmission line.

In the drawing wherein like reference char-

acters designate the same parts in all figures, 1 designates generally the body and 2 the cap of a plug-like fixture which is adapted to be attached by means of a dependent metal strap 3 and a bolt 5 to a water pipe 6 or other convenient "ground." In one practical embodiment of the invention both the body 1 and the cap 2 of the fixture were injection-molded of a thermo-setting synthetic resin (in this case "Bakelite") and were of the 10 illustrated substantially cylindrical shape; the dimensions of the cylinder being approximately 2½" long, 1¼" in diameter.

As shown more clearly in Fig. 1, the upper or cap-end of the body 1 is provided with external 15 threads 6 and this threaded portion is divided by a transverse slot 7 of a width sufficient to accommodate a tape-like electrical transmission line 8 containing two parallel wires 9 and 10 (see Fig. 2). This slot 7 communicates with a central 20 cavity 11 which has a preferably concave bottom surface 12 and a rectangular opening 13 in said surface for accommodating the metal attaching strap 3. The strap 3 is not molded into the insulating body 1 but is simply seated therein by 25 folding the strap and passing the adjacent ends thereof through the opening 13 (from the interior of the cavity) and spreading an intermediate section 3a (Figs. 1 and 3) of the strap over the concave bottom 12 of the cavity. The spread 30 or collapsed strap section 3a on the concave inner bottom surface of the cavity provides a seat for a spring which, in the instant case, is shown in the form of a U-shape or trough shape member 14 which may simply be dropped into the cavity 35 with its rounded bottom resting upon the spread-out portion 3a of the strap. The upwardly extending arms of the spring 14 are preferably bent outwardly, as indicated at 14a, Fig. 3, to form a pedestal for a disc-like insert 15 constituted of a resistive material, such as carbon. This insert is designed to provide a leakage path, from each of the conductors 8, 10, to ground, of approximately 30,000 ohms.

The cavity 11 has two oppositely located shoulders 16 moulded therein, at a level slightly below that of the base or bottom of the transverse slot 7 and these shoulders serve as a support for a rectangular insert 17 constituted of insulating material. This insert 17 is provided with a number (in this case, four) of spaced-apart metal pins 18, 18a, etc., which extend upwardly through said insulating material and terminate at a level slightly above that of the base of the slot 7 in the path of the tape-like transmission line 8. 55 The points of these pins 18 are designed to pierce

the insulating tape 8 within which the transmission wires 9 and 10 are enclosed and are mounted on the insert 17 in register with the said wires so that they each form a conductive connection between the wires and the resistive insert 15, when the tape is pressed down on the pins.

The force required to cause the pins 18 to penetrate the tape 8 and to bring them into conductive engagement with the separate wires 9 and 10 is applied by screwing the cap 2 down on the body 1 of the unit. To this end, the cap is provided with internal threads 19, which engage the complementary external threads 6, and with a centrally-located protuberance 20 whose leading end bears against the tape 8 when the tape is within the slot 7 and the cap is screwed down on the body of the unit.

It will be observed upon inspection of Fig. 3 that the biasing force applied to the underside of the resistive insert 15 by the spring 14 causes the said insert to bear against the heads (or lower terminals) of the pins 18 and thus ensures excellent electrical continuity between the transmission wires 9 and 10, the pins 18, the resistor 15, the spring 14 and the grounding strap 3.

Prior to use, i. e. when the transmission line 8 is not in the slot 7, the force of the spring 14 may lift the insert 17 upon which the pins 18 are mounted, upwardly against the central protuberance 20 on the cap. Accordingly, the leading end of this protuberance 20 is provided with a circular recess 20a (Fig. 3) within which the points of the pins are accommodated so that they will not be bent out of shape by contact with said surface.

The lower surface of the receptacle 1 is preferably concave in outline as indicated at 21 so that the unit may be mounted directly on the water pipe 5 or other fixture to which the grounding strap is affixed. The said metal strap 3 is provided with a number of spaced-apart mounting holes 22 so that it may be affixed by its bolt 4, to a pipe of substantially any standard size.

Since the "tap" of the present invention dispenses with the necessity of slitting the transmission line 8 and spreading its wires 9 and 10, its installation can introduce little or no change in impedance or "electrical bump" in the high frequency transmission system. It will likewise be apparent that the simple, inexpensive and trouble-free construction of the said tap permits it to be installed and used with entire safety in any conventional home-television installation.

What is claimed is:

1. A tap for grounding an insulated transmission line, said tap comprising an insulating receptacle having an aperture therein through which said transmission line is adapted to pass and containing a cavity which communicates with said aperture, a plurality of pins mounted in said cavity with the points of said pins projecting into said aperture in register with said transmission line whereby said points are adapted to penetrate the insulation on said line, a resistive element in said cavity adjacent to said pins, conductive means for biasing said resistive element into engagement with said pins, and a conductor connected to said biasing means within said cavity and extending to the exterior of said receptacle.

2. The invention as set forth in claim 1 and wherein said conductor comprises a metal strap both ends of which extend to the exterior of said receptacle.

5. A tap for grounding a plural wire transmission line comprising an insulating body having an opening therein through which said transmission line is adapted to extend, a plurality of pins individual to respective ones of said wires projecting into said opening in a direction normal to the direction of extension of said transmission line, means for pressing said wires into intimate contact with said pins, a resistive element within said insulating body in contact with said pins, and a conductor electrically connected to said resistive element and extending to the exterior of said insulating body for grounding said wires through said pins and resistive element.

4. A tap for grounding a tape-like parallel wire transmission line, said tap comprising an insulating structure having a channel in a surface thereof within which said tape is adapted to be laid and containing a cavity beneath said channel, a plurality of pins projecting from said cavity into said channel with the points of said pins positioned to engage separate ones of said parallel wires when said tape is pressed down thereon, an insert constituted of resistive material in said cavity adjacent to the inner ends of said pins, a spring in said cavity for biasing said resistive insert into engagement with said pins and a conductive connection including said spring extending to the exterior of said cavity for grounding said parallel wires through said resistive insert.

35. 5. A tap for grounding a plural wire transmission line comprising, an insulating body containing a cavity and having a transverse slot adjacent to one end of said cavity for receiving said transmission line and an axially extending aperture in its opposite end through which a grounding strap extends, a spring within said cavity in contact with said strap, a disc of resistive material on said spring, an insulating support mounted within said cavity, a plurality of pins extending through said support into engagement with said resistive material and with the points of said pins in register with the plural wires in said transmission line, and an adjustable cap on said insulating body for exerting a clamping force on said tape against the biasing force of said spring whereby said plural wires are brought into electrical engagement with said grounding strap through said pins, said resistive element and said spring.
